UNITED STATES PATENT OFFICE.

THEODORE A. B. PUTNAM, OF NEW YORK, N. Y.

RAILWAY-CROSSING GATE OR SIGNAL.

SPECIFICATION forming part of Letters Patent No. 284,669, dated September 11, 1883.

Application filed September 27, 1882. (No model.)

To all whom it may concern:

Be it known that I, THEODORE A. B. PUTNAM, a resident of the city, county, and State of New York, have invented certain new and 5 useful Improvements in Railway-Crossing Gates or Signals and in Means for Automatically Operating them, of which the following is a specification:

Wherever a street or road crosses a railway-track on a level it is desirable for the prevention of accidents that a gate be closed across the road or street shortly before each train reaches the crossing and opened immediately after the passage of the train, in order to warn 15 approaching vehicles and pedestrians from attempting to cross the track until after the train has passed. For this purpose hand-operated gates are commonly used on street-crossings in cities, and on country roads a flagman 20 is usually stationed or else the crossing is entirely unprotected. The object of my invention is to provide a gate which will close across the street or road automatically upon the approach of a train within a certain distance and 25 open automatically when the train has passed; or, instead of a gate, a warning-signal may be used, which will travel into view, preferably across the road or street, in advance of the approach of a train and return to its normal position when the train has passed.

My invention is shown in the accompanying drawings, wherein Figure 1 is a front elevation of my gate when open, the railway-track being in longitudinal section. Fig. 2 is a horizontal section of the gate cut on the line 2 2 in Fig. 1, and a plan of the track, which may be the track of a single-track road or one track of a double-track road. Fig. 3 is a transverse section of the track cut in the plane of the line 3 3 in Fig. 2. Fig. 4 is a transverse section of a portion of the gate cut on the line 4 4 in Fig. 1 and looking in the direction of arrow 4. Fig. 5 is an enlarged rear view of a portion of the gate and an edge view thereof. Fig. 6 is a 40 front elevation of the electro-magnetic releasing detent. Fig. 7 is a plan of Fig. 6. Figs. 8 and 9 are fragmentary views of the gate while closed in two different positions; and Figs. 10 and 11 are diagrams showing the track in plan 45 and illustrating two means of operating the gate from distant signaling points on the track.

Let A designate the track, and B the road or street which crosses it.

In the drawings I have shown the gate as adapted for use on a country-road crossing. 55

Referring particularly to Figs. 1 and 2, C is the vertical framing of the gate, shown as consisting of three upright posts, D D D, and a horizontal cross-bar over the top to brace them. Other braces may also be added, if necessary, 60 and the working parts may be covered by a hood; but for the sake of perspicuity I have shown all the parts in their simplest form.

E is a fence, being part of that extending along the railway-track, and which also extends between the middle and right-hand posts D. Between the middle and left-hand posts is the road-crossing.

To the middle post, near the top of the latter, is pivoted or fulcrumed a vibrating lever 70 or walking-beam, F, which extends to the right and left beyond the outer posts. This beam forms or bears a track on which rolls a carriage, G, forming part of the gate. This carriage may be made in many different ways, 75 that shown consisting of an upper bar, a, above the beam F, and a lower bar, b, below it, both parallel with it, and connecting-bars c extending between them in front of the beam, vertically and diagonally, to form a rigid 80 frame. Grooved wheels d, journaled on pins on the bar a, roll on the top of the walking-beam, and another like wheel, d', rolls against its bottom edge, and prevents the carriage G from becoming vertically displaced. From 85 the bar b is suspended the gate proper, which I have shown as consisting of a series of strips, e e, of flexible substance, as canvas, leather, or sheet metal, painted in a conspicuous manner, and suspended at their upper ends by 90 flexible links, as shown in Fig. 5. These strips are designed to present an impassable appearance, so that a driver finding the gate closed will not attempt to pass; but if the gate should be released while a person or team is passing, the strips will part or yield and inflict no 95 damage. These strips and the carriage together constitute the gate, which I shall refer to as a whole by the letter H. Instead of flexible strips, hinged bars might be used, so hung 100 that they will yield to pressure from the track, but are rigid to pressure toward the track,

thereby resisting any attempt to get upon the track, but permitting a person who has crossed the track to escape through the gate.

Fig. 1 shows the parts in their normal positions. The gate is open, and the walking beam is tilted with its arm supporting the gate uppermost, so that the gate tends to roll down along the beam and close itself; but it is restrained from so doing by an electro-magnetic 100 10 15 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 supposed to be a half-mile away from the crossing in both directions. The nearer signaling-points, from which the magnet M' is excited to open the gate, are lettered $S' S'$, and may be 5 assumed to be one-eighth of a mile from the crossing in both directions. These distances are of course not essential.

There is one point S and one point S' on each track, and at each of these points a break 10 or insulation is effected between adjoining rails on one side of the track, and when a locomotive crosses this insulation it bridges it through its conducting-wheels and frame, and so closes the circuit.

15 The magnet M connects through one of its terminals with a fixed contact-spring, m , and the magnet M' with a like spring, m' . The beam F bears two similar springs, n and n' , on its opposite arms, so arranged that when in 20 its normal position, Fig. 1, its spring n touches spring m , thus connecting the beam with magnet M , while its spring n' is out of contact with the spring m' , thus insulating the beam from magnet M' , Fig. 10. When the lever tilts to 25 its opposite position, this result is reversed, (Fig. 9.) The beam is of conducting material, and is connected to one pole of a battery, P , the other pole of which is connected by a wire, 1, to the insulated rails 2 2. The rails 3 3 at 30 $S S$ are connected by wires 4 4 to the magnet M , and the rails 5 5, at the points $S' S'$, are connected by wires 6 6 to the magnets $M' M'$. The operation is as follows: Suppose a train 35 be approaching the crossing on either track in the direction of the arrow. When the locomotive crosses the insulation at S , it closes the circuit, as described, and the current from the battery P flows through wire 1, rail 2, rail 3, wire 4, magnet M , springs $m n$, and walking- 40 beam F back to the battery. Thus magnet M is excited, and the gate closes. When the locomotive reaches treadle K , the beam F is tilted to the opposite inclination, breaking contact at $m n$ and establishing connection with 45 magnet M' through springs $m' n'$. When the locomotive reaches the point S' and bridges the insulation, the circuit is again closed, and flows from battery P through wire 1, rail 2, rail 5, wire 6, magnet M' , springs $m' n'$, and 50 beam F , thereby exciting magnet M' , and again releasing the gate, which opens and sets itself ready for the next operation.

This electrical arrangement is not necessarily the preferable one; but it is suitable for 55 application to most railway-crossings, and will serve to illustrate the principle on which my gate may be electrically actuated.

I propose making the means for electrically operating this and similar gates the subject 60 of a separate application for patent.

Fig. 11 of the drawings shows a means of operating my gate mechanically, the two tracks being shown in plan, and the treadles, walking-beam, and detents in front elevation. The 65 electro-magnets, circuit-wires, and insulations are entirely omitted, and at each signaling-point $S S'$ a treadle, K' , is arranged. To each

of these treadles a pull wire, cord, or chain is connected, which extends thence to and is connected with the corresponding detent. The 7c wires $w w$ from the two points $S S$ both lead to the detent I , and the wires $w' w'$ from the points $S' S'$ lead to the detent I' . When a train passes any one of these points its wheels depress the treadle K' there located, and so pull 75 on the wire which communicates the motion to the corresponding detent which it withdraws and frees the gate. In lieu of this particular construction, pneumatic tubes might be used and the treadles made to operate bellows 80 to force a pressure of air into the tubes, which would act on other bellows at the crossing connected with the detents.

If desired, a gate may be arranged at each side of the track, in which case it will not be 85 necessary to construct and operate both gates according to my invention; but one of them may be a mere passive gate rolling on a fixed level track or bar to be rolled back and forth by the other. A light frame may extend 90 across the track to connect the two, high enough up to permit the train to pass beneath it.

Instead of being constructed of flexible strips 95 $e e$, the gate H may, if preferred, be made of rigid bars, as gates are usually constructed. Further, instead of a gate the carriage G may 100 carry a mere signal, as a flag, designed to warn approaching teams or pedestrians of the proximity of a train. As a signal its use is not necessarily confined to crossings, but it 105 may be used as a visual block, signal, or semaphore to roll across the track into sight of the engineer upon the passage of a train, and be returned when the train reaches the next signaling-point beyond.

It is obvious that the gate or signal may be 110 returned or opened immediately upon the passage of the train by omitting the detent I' and magnet M' .

I claim as my invention—

1. The combination, with a railway-track, of a gate or signal at a road or street crossing adapted to close across said road or street and to open and clear the same, means for causing said gate when standing normally open to close 115 itself, a detent normally restraining said gate from so closing, a signal-transmitting point located at a distance up the track, suitable connection between said detent and said point, whereby on the passage of a train 120 past such point the detent is withdrawn and the gate permitted to close, and the treadle on the track in proximity to the crossing adapted when acted on by the passage of a train to impart to said gate a tendency to open, substantially as and for the purposes set forth.

2. The combination to form an automatic railway gate or signal, of a walking-beam or lever normally tilted to an inclination, a carriage rolling thereon and normally supported 130 on its higher arm, a gate or signal depending from said carriage, a detent restraining said carriage from rolling down said beam, suitable means connected with a remote signal-trans-

mitting point for withdrawing said detent, and a treadle connected with said beam and adapted when depressed by the passage of a train to tilt said beam to the opposite inclination, 5 and thereby impart to said carriage a tendency to travel to the arm of the beam on which it is normally supported, substantially as set forth.

3. The combination, with a railway-track, 10 of a gate or signal at a road or street crossing, adapted to close across said road or street and to open and clear the same, means for causing said gate, when standing normally open, to close itself, a detent normally restraining said 15 gate from so closing, a signal-transmitting point located at a distance up the track, suitable connection between said detent and said point whereby on the passage of a train past such point the detent is withdrawn and the 20 gate permitted to close, a treadle on the track in proximity to the crossing adapted when acted on by the passage of a train to impart to said gate a tendency to open, a detent engaging said gate when closed and restraining 25 it from opening, a signaling-point on the track beyond the crossing, and suitable connection between said point and said detent whereby the passage of the train past said point will cause the withdrawal of the detent and permit 30 the gate to open, substantially as set forth.

4. A walking-beam arranged approximately parallel to a railway-track, with one of its arms extending over and across a road or street crossing said track and standing normally inclined with said arm lower than its 35 opposite arm, in combination with a carriage adapted to roll on and along said beam, with means for tilting said beam to the opposite inclination, and with suitable detents for retaining said carriage at either end of said beam, and restraining it from rolling down its inclined 40 surface, substantially as set forth.

5. As a means of operating railway gates or signals, a walking-beam adapted to be inclined 45 in both directions from the horizontal and normally standing inclined in one direction, in

combination with means for causing it to tend always to assume such position, with a treadle on the track adapted to be operated by the passage of a locomotive or train, and suitably connected with said beam whereby the latter will be tilted to the opposite of its normal position on the operation of said treadle, with a detent adapted to engage the beam when so shifted from the treadle, and suitable means, substantially as set forth, for disengaging said detent, and thereby releasing the walking-beam. 55

6. The combination, to form a railway-crossing gate or signal, of a walking-beam arranged alongside the track and extending 60 across the street or road, counterweighted at one end or otherwise tending to assume an inclined position, a carriage rolling along said beam, suitable detents adapted to engage said carriage when at opposite ends of said beam, 65 and to restrain it from running down the inclined surface thereof, a treadle on the track adjacent to the crossing, suitable connecting mechanism between said treadle and walking-beam whereby the passage of a train past the 70 crossing operates said treadle and tilts said beam into a position inclined in the opposite direction to its normal position, and a suitable pawl or detent adapted to engage the beam when so tilted and restrain it from returning 75 to its normal position, substantially as set forth.

7. The combination of walking-beam F, its counter-weight F', carriage G, detents I I', adapted to engage said carriage, track-treadle K, suitable connecting mechanism between it 80 and said beam, and detent L, adapted to engage said beam when tilted to the opposite of its normal position, and to be disengaged by impact of said carriage, substantially as set forth.

In witness whereof I have hereunto signed my name in the presence of two subscribing witnesses.

THEODORE A. B. PUTNAM.
